(57) **CLAIM**

I claim the ornamental design for an air vehicle rotatable wind-driven sleeve, as shown and described.

DESCRIPTION

FIG. 1 is a perspective view of an air vehicle rotatable wind-driven sleeve, showing my new design;

FIG. 2 is a top plan view thereof;

FIG. 3 is a bottom plan view thereof;

FIG. 4 is a left-side elevational view thereof;

FIG. 5 is a right-side elevational view thereof;

FIG. 6 is a top plan view thereof; and,

FIG. 7 is a bottom plan view thereof.

The broken lines showing a rocket in FIG. 1 depict environmental matter and form no part of the claimed design.
